George H. Jacks
ATTORNEY

UNITED STATES PATENT OFFICE

NATE MOCK, OF BERLIN, GERMANY

ASH TRAY

Application filed March 8, 1928, Serial No. 260,226, and in Germany March 11, 1927.

My invention relates to improvements in smokers' ash-trays, and the object of the improvements is to construct an ash-tray so that the smoker is not enabled to extinguish the cigar or cigarette by pressing the same on the tray, and in which the tray is provided with cells of a cross-sectional area substantially corresponding to the thickness of cigarettes or cigars, so that for extinguishing the cigarette or cigar the smoker puts the cigar or cigarette into one of the cells. Other objects of the improvements are to construct the tray so that the ash put into the same cannot be seen, and that it cannot be blown away by draughts.

For the purpose of explaining the invention several examples embodying the same have been shown in the accompanying drawing in which the same letters of reference have been used in all the views to indicate corresponding parts. In said drawing,

Fig. 1 is an elevation showing an ash-tray for cigarette smokers,

Fig. 2 is a top plan view of Fig. 1,

Fig. 3 is an elevation similar to the one illustrated in Fig. 1 and showing a modification suitable for cigar and cigarette smokers, and

Fig. 4 is a top plan view of Fig. 3.

In the example illustrated in Figs. 1 and 2 the ash-tray comprises a box or dish of any desired form and made from metal, porcelain or the like. Within the said dish or box there is a grid *b* dividing the whole area of the dish into cells *d*, the area of the said cells being such that a cigarette can be readily put into the same. Preferably the grid *b* is made from thin strip metal.

In the modification shown in Figs. 3 and 4, the grid *b* is constructed so as to provide cells *d* corresponding in size to the diameter of cigarettes, and larger cells *c* corresponding in size to the diameter of cigars.

The ash-tray can be used in the usual way for striping the ash from cigars or cigarettes, the ash falling to the bottom of the tray, particularly if the grid *b* is made from thin strip metal or the like. Thus the ash is withdrawn from view, so that even after use the tray has a tidy and clean appearance.

Further, the ash is safely kept within the cells, and it cannot be blown out in case of a draught of air.

What I claim is:—

1. An ash tray comprising a dish containing a grid having narrow partitions and forming a plurality of cells covering the entire area of said ash tray. 55
2. An ash tray comprising an open-top rectangular dish containing a grid having narrow partitions abutting the bottom of said dish and forming a plurality of cells covering the entire area of said ash tray. 60
3. An ash tray comprising a dish containing a grid forming a plurality of cells covering the entire area of said ash tray, the upper horizontal edges of said dish and said grid individually offering substantially no supporting surface. 65
4. An ash tray comprising a dish containing a grid formed by a connected series of cells, the tops of the walls of said cells offering substantially no supporting surface. 70
5. An ash tray comprising a dish containing a grid forming a plurality of rectangular cells covering the entire area of said ash tray, 75 the depth and area of said cells being adapted to prevent the access of air to the bottom thereof when containing a cigarette.
6. An ash tray comprising a dish containing a grid forming a plurality of rectangular cells covering the entire area of said ash tray, the area of some of said cells being adapted to receive cigarettes and the area of the remaining cells being adapted to receive cigars. 80

In testimony whereof I have affixed my signature.

NATE MOCK.
